UNITED STATES PATENT OFFICE.

ARTHUR E. WILDE, OF NEW YORK, N. Y.

SYRINGE.

1,114,561.

Specification of Letters Patent.

Patented Oct. 20, 1914.

Application filed May 24, 1913. Serial No. 769,749.

To all whom it may concern:

Be it known that I, ARTHUR E. WILDE, a citizen of the United States, residing at New York city, in the county of New York and State of New York, have invented new and useful Improvements in Syringes, of which the following is a specification.

The general object of the invention is to improve the construction of douche cups which are permanently associated with the nozzles of syringes in point of anti-leaking properties especially between the edge of the cup and the parts of the body to which the edge is applied when in use. And to this end the invention resides in forming the cup so as to expand upon the entrance thereto of the discharged irrigating fluid, whereby to afford sufficient volume for the said fluid and the air entrapped in the cup when the same is brought to bear on the portions of the body with which the cup is used in connection.

Other objects will appear and be better understood from that embodiment of my invention of which the following is a specification, reference being had to the accompanying drawing, forming part hereof, in which:—

Figure 1 is a side elevation of the invention. Fig. 2 is a sectional plan on the line 2—2 of Fig. 1. Fig. 3 is a view looking at right angles to Fig. 1 showing the cup in vertical cross section. Fig. 4 is a detail contracted longitudinal section of the nozzle.

The syringe comprises a reservoir *a* and a nozzle *b*. The reservoir *a* may be of any desired construction and adapted to be suspended for feeding the irrigating fluid by gravity, or as shown, this reservoir may be in the form of an ordinary aspirator and connected directly to the nozzle *b*, in which instance, the usual tube ordinarily employed for connecting the nozzle with the reservoir in a gravity feed device, is eliminated.

As shown in Fig. 4 the nozzle is made up of the sections 5—6 and 7, the first of which has a tapered passage 8 and reduced and exteriorly screw-threaded at the end portion 9, whereby to provide a seat for the gravity valve 10 which controls the passage 8 and for connection with the screw-threaded counter-bored portion 11 of the section 6. The said section 6 carries a spider 12 to limit the movement of the valve 10 in one direction. The section 6 is contracted at one end as indicated at 13, and forms the inner wall

of a chamber 14 whose outer wall is formed by the section 7 which is passed over the contracted portion of the section 13 and internally screw-threaded and screwed onto a screw-threaded portion 15 of the said section 6. The outer surfaces of the sections at the joints thereof are coincident for obvious reasons and communication between the passage of the section 6 and the chamber 14 is had through lateral openings 16 in the contracted portion 13 while the discharge opening 17 of the chamber 14 is located centrally of the free end surface of the section 7. The section 5 has a lateral port 18 surrounded by a circular casing 19 which is exteriorly screw-threaded for a cap or bonnet 20 which is centrally pierced as indicated at 21. A valve 22 located in the casing 19 controls passage through the ports 21 and 18, the said valve 22 like the valve 10, being noncylindrical in contour, whereby to insure against turning and to effect proper seating, the movement of this valve 22 being limited by the presence of a spider 12¹.

Now with this construction it will be manifest that upon the application of sufficient pressure to force liquid upwardly through the nozzle *b* the valve 10 will open under such pressure and the same will operate to close the valve 22. The opening of the valve 10 permits the fluid under pressure, to enter the section 6 and pass outwardly through the openings 16 and 17 and into the part to be douched or irrigated. Now when the bulb *a* is used and compressed to eject the fluid the valve 10 will return to its seat when the pressure is removed from the said bulb *a* and the fluid returning from the parts into which it has been directed by the compression of the bulb, will, upon the closing of the valve 10 be prevented from entering the chamber 14 by virtue of the presence of the air cushion therein, consequently the liquid will flow down the sides of the nozzle and open the valve 22 upon passing into the port 21 and thence return to the bulb after, however, the said liquid has entered the cup *c* about to be described. The said cup *c* is preferably formed of soft rubber and its upper edge 23 is reinforced by beading and conforms in contour to the contour of the parts to which it is to be applied. The bottom of the cup *c* is centrally provided with an opening surrounded by a thickened bushing 24 which, by virtue of its size and the inherent resilient properties thereof, closely

fits the base portion of the nozzle *b* below the valve casing 20. The side walls 25—25 of the cup are depressed longitudinally or bulged inwardly prior to vulcanizing so as 5 to normally occupy the position shown after the cup is vulcanized. These side walls are of relatively thin rubber and portions of their inwardly bulged surfaces normally bear on the nozzle *b*, and when so bearing it 10 will be observed that the volume of the cup is relatively small. Now upon fluid entering the cup from the irrigated parts as previously stated, the side walls 25 will be gradually pressed outwardly to the position 15 shown by dotted lines in Fig. 3 as the cup gradually fills, hence the volume of the cup will be increased beyond the normal. Now by virtue of this increase of volume on the part of the cup, sufficient room will be afforded for the liquid entering the cup and the air previously entrapped by the act of bringing the upper edge of the cup in contact with the body, hence the air cushion will afford no resistance to the entrance of the 20 fluid into the cup and there will be no tendency of the air or liquid to escape between the edge of the cup and the parts of the body upon which it bears, consequently the 25

said parts and those forming continuations thereof will be kept dry throughout the operation of douching or irrigating.

What is claimed as new is:

1. In combination with a syringe; of an expandible douche cup surrounding the nozzle of said syringe the walls of said douche cup being normally collapsed and arranged so as to be projected outwardly by the pressure of liquid entering the cup.
2. In combination with a syringe; of a normally collapsed douche cup surrounding the nozzle of the syringe and having side walls adapted to be expanded under the pressure of fluid entering the cup.
3. In a syringe, the combination with a nozzle; of a normally collapsed douche cup connected with the nozzle adapted upon the introduction of fluid thereinto to increase in volume substantially in proportion to the amount of fluid so introduced.

In testimony whereof I affix my signature in presence of two witnesses.

ARTHUR E. WILDE.
